R. O. McASSEY,
PRIMING DEVICE FOR GASOLENE ENGINES.
APPLICATION FILED SEPT. 5, 1919.

1,344,805.

Patented June 29, 1920.

INVENTOR
Rollin O. McAssey.

UNITED STATES PATENT OFFICE.

ROLLIN O. MCASSEY, OF SAN DIEGO, CALIFORNIA.

PRIMING DEVICE FOR GASOLENE-ENGINES.

1,344,805.

Specification of Letters Patent. Patented June 29, 1920.

Application filed September 5, 1919. Serial No. 321,934.

To all whom it may concern:

Be it known that I, ROLLIN O. MCASSEY, a citizen of the United States, and a resident of San Diego, in the county of San Diego and State of California, have invented a new and useful Priming Device for Gasolene-Engines, of which the following is a specification.

My invention relates to devices for introducing an explosive liquid into the carbureter independently of the regular means used when running.

The object of my invention is to provide a simple, cheap and easily installed device which will be easily operated and which can be attached to a carbureter without alteration of the carbureter except the removing of the needle valve.

Figure 1 represents a fragmentary side elevation of a manifold and Holly carbureter, such as is used on the engines of Ford automobiles, showing my invention mounted in said carbureter in place of the regular needle valve; Fig. 2, a plan view of my invention, drawn to an enlarged scale; and Fig. 3, a vertical central section of the device.

Similar reference characters refer to like parts throughout the several views.

The numeral 1 denotes a Holly carbureter; 2, a manifold partly broken away; 3, the stem of my invention; 4, the reservoir; 5, the lid mounted on said reservoir; 6, the conduit leading from the reservoir into the conduit 7 in the stem 3, said stem 3 being provided with a knob 8 having holes 9 therein.

To install the invention, the regular needle valve of the Holly carbureter is re-

moved and my invention substituted therefor, as shown in Fig. 1.

In cold weather when the engine is hard to start, it has been found that a small quantity of ether introduced within the carbureter will cause the engine to start more readily than if gasoline alone were relied upon. With my invention the ether is first poured into the reservoir 4 and runs down through the conduit 6 into the conduit 7 and thence into the carbureter. The stem of my invention is like the regular needle valve except the conduit 7, and performs the same function as the regular needle valve.

What I claim as new and desire to secure by Letters Patent is:

1. A device of the class described comprising a needle valve having a reservoir thereon and a conduit therein connecting said reservoir with the interior of the mixing chamber of a carbureter in which said needle valve may be mounted, adapted to convey a liquid from said reservoir to said mixing chamber; for the purposes set forth.

2. A device of the class described, comprising a needle valve adapted for use in a carbureter, said needle valve having a conduit therein, leading from the top thereof into the mixing chamber of the carbureter in which it is mounted; and a reservoir mounted on the top of said needle valve and having a conduit connecting with said first named conduit; for the purpose of conveying an explosive liquid from the outside of the carbureter into the mixing chamber thereof.

ROLLIN O. MCASSEY.
